Des. 214,350
Patented June 3, 1969

214,350

JEWELRY DISPLAY STAND

Lester Silverman, 77 Cold Brook Drive,
Cranston, R.I. 02910

Filed May 20, 1968, Ser. No. 11,998

Term of patent 14 years

Int. Cl. D20—02; D6—01

U.S. Cl. D80—9

FIG. 1

FIG. 2

FIG. 3

FIG. 4

FIG. 5

FIG. 6

FIG. 7

FIG. 1 is an elevational view of a jewelry display stand showing my new design;

FIG. 2 is a top plan view thereof;

FIG. 3 is a bottom plan view thereof;

FIG. 4 is a horizontal sectional view taken along line 4-4 in FIG. 1;

FIG. 5 is an elevational view 45° removed from the view illustrated in FIG. 1;

FIG. 6 is a vertical sectional view taken along line 6-6 in FIG. 1; and

FIG. 7 is a vertical sectional view taken along line 7-7 in FIG. 5.

I claim:

The ornamental design for a jewelry display stand, substantially as shown.
